APPARATUS FOR RECONDITIONING THE INTERIOR OF CONTAINERS

Samuel F. Kimball, Portland, Maine, assignor to
The Portland Company, Portland, Maine, a corporation of Maine

Application April 2, 1935, Serial No. 14,284

17 Claims. (Cl. 221—69)

My present invention relates to improvements in apparatus for use in reconditioning the interiors of containers.

While many attempts have been made to cleanse the interiors of containers by machine, great difficulty has been encountered, particularly with those containers having bung holes in their ends. With containers of this type, drainage and drying were considered insurmountable obstacles.

In my copending application, Serial No. 689,425, I have shown and described apparatus to recondition the interiors of containers of this type. While the apparatus therein described has many other advantages, the use of means to exhaust the fluid from the lowest point inside the container is fundamentally the factor that makes the automatic or semi-automatic reconditioning of container interiors possible, though many other factors cooperate therewith to render container reconditioning effective and economical.

One of the factors determinative of the actual utility of apparatus of this type is the rapidity of operation. My invention makes it possible to solve the problem of drying the interior with certainty so that automatic or semi-automatic container reconditioning is attainable. With that fundamental solved, it is then possible to construct machinery that will be both economical and efficient. Prior to my invention, the uncertainty of efficient drying made it impossible to determine the many other problems that relate to efficiency and economy.

With containers having their bung holes in the ends, there is a real difficulty in that the bung holes are not only of different sizes but also vary in their positions in relation to the sides of the container. While containers of this type may be supported in canted position to collect the fluid, to reach the lowest point in every container to thoroughly dry its interior is a real problem.

In my present application, I have shown my solution of that problem by utilizing a fluid exhausting member that may be extended within any container to reach automatically the lowest point. I have provided a container receiver in which containers are held in a canted position. Because of the variations in the shortest distance between bung holes and side walls, my concept also includes means to permit the degree of inclination of containers to be varied to vary the position of the side wall in relation to the fluid exhausting means.

I have shown my new fluid exhausting member as applied to various types of equipment which

are representative of the individual requirements as determined by the quantities of containers to be reconditioned and the amount of capital outlay warranted.

Any type, while depending for its structure on a maximum capacity and the degree of automatic control desired, must include an adjustable fluid extracting member for real efficiency. I have, however, developed many features which are of real utility in any reconditioning apparatus.

The types shown in my present application are representative. I have shown my new fluid exhausting member as applied to the apparatus shown in my copending application, Serial No. 689,425, in which containers were progressively reconditioned. I have also shown new equipment of smaller capacity, in which a plurality of containers are reconditioned simultaneously. In these types, the necessary re-use of and controls for the fluids present problems which are not present in a third type in which containers are manually moved from station to station in each of which specific operations are performed.

Many other improvements in container reconditioning apparatus will be noted as the description of apparatus shown is developed in detail.

In the drawings:—

Fig. 1 is a section through a container receiver showing my improved fluid exhausting means as applied to one type of apparatus.

struction and the operative connection to the valves.

Figs. 16, 17 and 18 are cross sections along the lines 16-16, 17-17, and 18-18, respectively, of Fig. 15, and

Fig. 19 is a sectional elevation of the apparatus of Fig. 1.

In reconditioning containers, it is necessary to use suitable washing and rinsing fluids and air under pressure to cooperate with the fluid exhausting means in drying the interiors.

The controls for these elements vary with the different types and the greater the degree of automatic controls desired for the different operatives, 15 the more important is the inter-relation of the elements.

While in apparatus essentially automatic, the general principles generally follow those shown in my copending application Serial No. 689,425, its 20 specific features are of importance in all reconditioning apparatus, and the novel fluid exhausting means for use in reconditioning containers having bung holes in their ends may be best understood from a detailed description of a characteristic type.

The apparatus shown in Figs. 2 and 3 will be separately dealt with where a necessary description is required.

30 *The fluid circulating system*

For my apparatus I provide a housing structure having a front wall 1, a rear wall 2, and end walls indicated as at 3, a bottom 4, and a partition 5 which with the dividing wall 6 forms the 35 tank W for the washing fluid and the tank R for rinsing fluid (see Fig. 6).

In Figs. 5-9, the details of the tanks, the heating means, and the general system for the circulation of fluids may be best observed.

40 In Figs. 5 and 6, it may be seen that each of the tanks W and R is provided with steam coils 7 connected to any suitable source (not shown) by an inlet 8. A steam outlet 9 is provided which leads to a common discharge 10. The steam inlets 8 are controlled by the manually operated valves 11 and also by the valves 12 controlled by the thermostats 13.

50 The tanks W and R are filled through the fluid inlets 14 (see Fig. 9) which are controlled by the valves 15. Both of the tanks W and R are provided with a drain 16 controlled by the valves 17 (see Figs. 6 and 8).

55 In Figs. 5 and 6, the overflow system may be best seen. The fluid level in the tank W is maintained by means of the overflow 21 which communicates with the drainage pipe 22 (Fig. 5). Into this drain pipe 22 also leads the combination overflow and scum trap 18 for the rinsing tank R. The tank W is provided with a separate scum trap 19 which extends through the casing wall 2, as shown in Figs. 6 and 7, and which is controlled by the valve 20. This scum trap is necessary because the scum in the tank W is generally of an oily nature and its disposal is frequently governed by statute or ordinance. Any scum in the rinsing tank R however may be passed off through the drainage pipe 22. The overflow 21 in the washing fluid tank W extends well below the desired fluid level so as to be free of the scum which is disposed of as stated above through the trap 19.

70 A pump 23 has an intake 24 from the tank W and an outlet pipe 25 which, as is shown in Fig. 9, extends the length of my apparatus and is bent back upon itself and provided with a pressure

valve 26 disposed to discharge fluid back into the tank W.

A pump 27 has an intake 28 from the tank R and an outlet pipe 29 extending substantially the length of the apparatus parallel to the pipe 25 and is bent back and provided with a pressure valve 30 to return fluid to the tank R.

A conduit 31 from a suitable source of air under pressure (not shown) is disposed between the pipes 25 and 29.

10 In Figs. 1, 7 and 8, I have shown the upper portion of my device. The front wall 1 and the partition 5 have flanges 1^a and 5^a, respectively, on which the container receivers 32 are seated.

The receivers are formed with sloping side and 15 bottom walls 33. At a suitable place on the bottom or floor of the receiver 32 I position my nozzle and siphon over an aperture 34. When not given particular attention as in Figs. 1 and 2 my nozzle and siphon are generally indicated as at 35. 20

The receivers 32 are provided with a cross member 36 which is recessed as at 37 to support one side of a container having a bung hole in its side so that the nozzle and siphon 35 will extend within a bung hole. Containers having their bung holes 25 B in the end are supported in a canted position in the receivers 32. This is effected by utilizing a support 38 substantially below the level of the cross member 36 so that such a container may be supported to permit the nozzle and siphon 35 to 30 enter the bunghole B of the container.

Containers which are to be supported in canted position present another problem. The edges of the bung hole either extend outwardly or inwardly of the container head and the length of the chimes 35 varies. As it is necessary to keep the lowest point of container within reach of the siphon I provide the block 38 for use with containers having a chime inadequate to be used to position the container properly. The block 38 is adapted to support the container bevel adjacent the bung hole. A second support 38^a is adapted to support the chime of certain types of containers. Both of the supports 38 and 38^a are supported by a shelf 38^b which is adapted to support the edges of still 45 different types of containers.

As shown in Fig. 9 the space between receivers 32 may be covered as by the plate S.

Below each receiver 32 I position a valve casing 39 which extends through the front wall 1 to 50 which it is locked by a threaded cap 40. The casing 39 is supported rearwardly by a flanged member 41 which is inserted through the partition 5 and suitably secured to the casing 39 as at 42. The top of the member 41 is slotted as at 55 43 for a purpose hereinafter to be described.

The valve casing 39 is provided with an inlet aperture 44 into which is threaded a pipe 45 tapped into the washing fluid pipe 25. A second aperture 46 receives a pipe 47 connected to the 60 rinsing fluid pipe 29 and a third inlet 48 connects the air conduit 31 to the casing 39.

65 Outlets 49 and 50 are connected to a common outlet 51 which leads to the nozzle, see Fig. 1, and the casing 39 is provided with another outlet 52 from which an air line 53 extends into the receiver to the nozzle and fluid exhausting means 55 as may be best seen in Fig. 15.

The details of the valve casing and the valve may be most clearly seen in Fig. 1. The valve 70 consists of a plurality of pairs of discs mounted on a stem 54 which is secured to an extension 55 by a pin 56 extending through the slot 43 in the member 41. This permits the valve to be easily removed for repair or replacement. The 75

extension 55 carries a cam contacting roll 57 which is supported by a slide 58 suitably supported between the rear wall 2 and the partition 5.

One pair of members 59 is adapted to define a passage between them to permit washing fluid to flow into the casing 39 at 44 and out through the outlet 49 to the delivery port 51.

Another pair of members 60 is adapted to connect the air inlet pipe 48 to the outlet 52 while a third pair of members 61 is adapted to be positioned to permit rinsing fluid to enter the casing 39 through the inlet 46 and to reach the outlet 51 through the delivery port 50.

The pairs of members 59, 60 and 61 are positioned so that when one inlet is connected to an outlet the other outlets are closed, and the stem 54 may be positioned to close all outlets. It will be also noted that if it is desired to change the valve from a position where one fluid may flow to a position where the other fluid may circulate, the valve will first open the air line. I therefore place a pair of drains 63 on each side of the air inlet 48 so that when the pair of members 60 is positioned to open the air line, adjacent members of adjacent pairs will permit fluid to flow back through the drains 63 from the outlets 49 and 50, thereby draining the valve casing 39 before the next fluid is permitted to flow.

I thread into the outlet 51 a valve 64 which may be operated by the handle 65 extending through the wall 1. A pipe section 66 having a flange 67 enters the aperture 34 in the receiver 33. The pipe 66 is threaded into the valve 64 and is threaded to receive a nut 68 by which a washer 69 may be compressed to seal the aperture 34.

Each of the receivers 32 is provided with a drain 70 disposed over a drainage conduit 71 which extends the length of my apparatus. The conduit 71 is supported on beams 72 braced as at 73. The valve drains 63 also discharge into the conduit 71.

The drainage conduit 71 is formed with a drain outlet 74 over the wall 6 dividing the tanks R and W. In Fig. 11 I have shown a valve 75 which is pivotally mounted as at 76 on the wall 6. The side walls of the valve 75 are sloped to bear against the bottom of the conduit 71 on either side of the drain 74 directing the fluid into either the tank W or the tank R. The pivot 76 extends through the partition 5 and is provided with a handle 77 (Fig. 11).

By the structure so far described, either washing or rinsing fluid may be circulated depending on the position of the delivery valve and the drain valve 75 as with the structure shown in my copending application, Serial No. 689,425. The delivery valve is identical and the circuits and controls have, in general, been modified only as required by the different types of apparatus illustrated.

The nozzle and siphon construction

The nozzle and siphon generally indicated at 35 may be best viewed in Figs. 1 and 2, while the 65 details are more clearly shown in Figs. 11 through 16.

The nozzle (Figs. 13-16) consists of a tube 80 mounted in a block 81 which is bolted as at 82 to the receiver 32 over the aperture 34 to receive either the washing fluid or the rinsing fluid according to the position of the valve in the casing 39. The upper portion of the tube 80 is bent to substantially the degree of inclination of a container when supported in canted position in 75 the receiver 32.

Suitably secured to the tube 80 and to the block 81 is a fluid exhaust tube 83. The tube 83 is closed at both ends, but is apertured as at 84 to receive the pipe 85 leading into the suction chamber 86. The tube 83 is bent similarly to the tube 80, but is shorter. The upper end of the tube 83 is shaped to present a surface substantially vertical.

A block 87 is secured to the tube 80. The block 87 is provided with a flange 88 which, with the upper end of the tube 80, receive the spray cap 89. The lower end of the block 87 is cut parallel to the upper end of the tube 83 to define the passage 90. The air line 53 (see Fig. 15) is provided with branch lines 91 and 92. The line 15 91 is connected to the suction chamber 86 and the line 92 extends upwardly adjacent the tubes 80 and 83 to which it is secured. The air line 92 extends through the passage 90 to discharge air into substantially the highest point in the 20 interior of containers and this inrushing air through the pipe 91 creates a suction in the chamber 86 which exhausts fluid from the container into the chamber 86 through the parts 83, 93, 94, 95 and 95', as hereinafter more fully explained.

At the bend in the tubes 80, 83, and 92, the tube 83 is apertured as at 93 and the hollow pivot 94 adapted to support the hollow arm 95 is threaded therein. The pivot 94 is provided with 30 a passage 96 to align with passage 95' in the arm 95 which may be pivoted downwardly a desired extent toward the lowermost point of the container to exhaust any fluid which may have been collected there.

A sleeve or extensible tip 97 is mounted on the arm 95. The arm 95 is formed with a groove 98 in which the lug 99 on the tip 97 slides to adapt its operating length to different sizes and styles of containers. The tip 97 is provided with a fluid 40 intake 100. The block 87 has a flange 88 serving as a stop for the arm 95 and tip 97 when in inoperative position as shown in Fig. 13.

The extensible tip 97 on the arm 95 is carried into the lowest point of the container before the 45 fluids or air are discharged into the container through the valve 39 by means to be later described in detail. It will be understood that as air is discharged through the pipes 91 and 92 (Fig. 15) any fluid in the container will be sucked 50 into the chamber 86 through the tip 97 and members 95, 94, 93, 83, 84, and 85, and from this chamber 86 it drains to the floor of the receiver 32.

The mechanism to move the arm 95 and extend the tip 97 to fluid exhausting position will be 55 later described after the general operating mechanism in different types of apparatus has been considered.

Apparatus operating mechanism

As the types of apparatus illustrated in Figs. 1 and 2 are operated differently, they will be separately described although the fundamental principles are the same.

In the form shown in Fig. 1 a driving motor 101 is located between the walls 2 and 5 (see Figs. 8 and 9). The motor 101 rotates a shaft 102 as by the belt 103. The shaft 102 is provided with worm gears 104 (see Fig. 1) in mesh with gears 105 on shafts 106 mounted on bearings 107 70 on the walls 2 and 5. Secured to each of the gears 105 are the operating cam wheels 108 (see Figs. 1, 7, 8 and 11).

On each of the shafts 106, is a cam wheel 108 having a series of cams on its face of different 75

shapes. These cams are adapted to contact the roll 57 to carry the rod 54 to position the pairs of members 59, 60, and 61 to control the fluids and air as desired.

5 The arrangement of cams on the cam wheel 108 is shown in Fig. 10. The cam 109 is adapted to move the roll 59 to permit the injection of washing fluid. The cam 110 is spaced to permit this operation to be continued for a desired length 10 of time and then to connect the air conduit for a length of time sufficient to permit the fluid to be exhausted from a container and the valve casing 39.

15 The cam 111 is adapted to close the air conduit and to open the rinsing fluid conduit while the cam 112 closes the rinsing fluid conduit and again opens the air conduit until the containers are thoroughly dried. At a predetermined point on the cam 109, all the conduits are closed.

20 As on a complete revolution of the cam wheel 108 a container is thoroughly reconditioned, I provide mechanism to shut off the driving motor 101 when all conduits are closed to the receivers 32.

25 This mechanism includes a switch generally indicated as at 113 secured to an end wall 3 as may be best observed in Figs. 11 and 12. The switch 113 is in control of an electric circuit to the driving motor 101 which circuit includes a 30 light 114 (shown only in Figs. 5 and 9). The switch 113 is adapted to close the circuit when the handle 115 pivoted as at 116 is held. A pivoted latch 117 controlled by the spring 118 holds the handle 115 when it is manually moved 35 into circuit closing position. The lower end of the latch 117 is provided with a stud 119.

Secured to the rear of the cam wheel 108 is a bracket 120 which receives the threaded bolt 121. The end of the bolt 121 is adapted to contact the stud 119 to open the circuit when all conduits to the receivers 32 are closed. As the bolt 121 is threaded into the bracket 120 very accurate adjustments may be made so that the latch 117 may be tripped at the correct moment.

45 As is shown in Figs. 9 and 11 one of the members 108 is provided with a cam 122. Guided in brackets 123 and 124 is a rod 125 having a portion adapted to bear against the surface of the cam 122. The rod 125 is provided with a flange 126 between which and the bracket 123 is a spring 127 urging the rod 125 against the cam 122. A lever 128 is pivoted at 128^a to the wall 5 and at 128^b to the rod 125. The lever 128 is forked as at 129 to straddle the handle 71 of the drain valve

50 75. The cam 122 through the mechanism just described is adapted to change the position of the valve 75 as the different fluids are injected, i. e., this cam has a surface adapted to move the valve 75 to position to guide the drainage from the receiver and valve when washing fluid is being delivered and during the succeeding drying operation back to the washing fluid tank W; and has another cam face adapted to position the valve 75 so as to direct the drainage to the rinsing fluid tank R when that fluid is being delivered to the containers and during the following drying period.

55 A third cam 130 is rotated by the shaft 106. This cam 130 is adapted to control the siphon positioning mechanism most clearly shown in Fig. 1 and which will be later described.

60 The type of apparatus illustrated in Fig. 2 is shown in detail in my co-pending application, Serial No. 689,425. This type differs from that

65 previously described primarily in the operation of the valves.

The container receivers 32 are mounted in a circular superstructure or support 131 rotatably mounted on a circular base 132. The superstructure 131 has a central supporting hub 131^a bearing on the base 132 which also supports a gear 131^b in mesh with a pinion 131^c rotated by any suitable means (not shown). The superstructure 131 is also supported by wheels 134 adapted to travel along the track 133 as the superstructure rotates.

70 In the base 132 are located the fluid tanks. From the washing fluid tank W, fluid is pumped through the conduit 25 which extends freely 15 through the hub 131^a and includes in the superstructure 131 a swivel joint 25^a. The conduit 25 includes a substantially circular portion under the receivers 32 and has, in its end, a pressure valve 26 disposed to discharge fluid into the tank 20 142.

75 The rinsing fluid conduit 29 extends from the rinsing fluid tank W and passes axially through the hub 131^a and includes a swivel joint 29^a and a substantially circular portion disposed under 25 the receivers 32 and has a pressure valve 29^b disposed to discharge rinsing fluid into the tank 143.

80 The air conduit 31, from any suitable source (not shown) has a swivel joint 31^a and a circular portion disposed under the receivers 32 between the conduits 25 and 29.

85 The type of apparatus shown in Fig. 2 may be appreciated when it is understood that the receivers 32, the valves 39, the nozzle and siphon construction are identical with the construction shown in Fig. 1 and they are held in operative position by a construction modified as required by the circular support 131. That is, while the valve casing 39 is held in the front wall 135 by 40 the cap 40 as in Fig. 1, the rear wall 136 is so positioned that the casing 39 is supported as at 137.

90 A circular wall 138 secured to the base 132 has a circular shelf 140 upon which are mounted 45 cams to be contacted by the rolls 57 to position the valves. These cams are adapted to control the valves in the same manner as the cams 109, 110, 111, and 112. On the shelf 140, I have shown the cam 141 which has positioned the valve to 50 close all conduits to the receivers 32. I have also shown another cam 141^b which has moved the valve to permit the injection of rinsing fluid into a container.

95 On the base 132 is a circular drain conduit 142 to receive the discharge from the pressure valve 26 in the washing fluid pipe 25. A similar conduit 143 is adapted to receive the discharge from a pressure valve in the rinsing fluid pipe 29. The dividing wall 144 is formed to permit the conduit 142 or the conduit 143 to receive drainage 60 from the receiver drains 70 and the valve drains 63 as they rotate over zones of fluid circulation as defined by the cams on the circular shelf 140.

65 Each of the conduits 143 and 144 is provided with a drain 145 disposed to permit the return of the fluids into the proper tank located in the base 132. If more than one tank is used for each fluid, I provide a drain 146 under each of the drainage outlets 145 which drains 146 are open as 70 at 147 to permit fluid to return to the tanks in the base 132. The drain 146 may be provided with a valve to direct the fluid from each of the outlets 145 towards whichever of the openings 147 is desired.

As the control of the circulation of the fluids and the air results from the rotation of the support 131 I position on the base 132 a cam 148 which is used to actuate the siphon positioning mechanism to be next described.

The siphon positioning mechanism

In the type of apparatus shown in Fig. 1, the cam 130 controls this mechanism.

10 I pivotally secure to the siphon tip 97, a bar 150 to which is pivoted a link 151 mounted on a pivot 152 in the container receiver 32. I secure another link 153 to the pivot 152 which bar 153 is connected to the bar 150 by the connecting 15 rod or bar 154.

15 The floor of the receiver 32 is formed with a housing 155 through which a rod 156 extends into the receiver 32. This rod 156 is pivotally connected to the link 153 by the link 157. In Fig. 1 20 the rod 156 is guided in the beam 72.

20 On the rear of the wall 5, I bracket a shelf 158 upon which I mount a stud 158^a surrounded by the spring 159. The wall 5 is apertured as at 160 to permit one end of the lever 161 pivoted as at 25 162 to the receiver 32 to lie between the cam 130 and the spring 159. The other end of the lever 161 is apertured to receive the rod 156 between which and a collar 156^a on the shaft 156 is a 30 spring 163. Below this end of the lever 161 is a pin 164 through the shaft 156.

35 In the position shown in Fig. 1, the siphon extension 97 and operating mechanism is shown in full lines in inoperative position and in dotted lines in operating position. In this position the cam portion 130^a is in contact with the lever arm 161^a and the spring 159 is correspondingly compressed. As the cam continues to rotate, this 40 engagement of cam portion 130^a and lever arm 161^a terminates and the tension on the spring 159 is released, and thereupon its normal action 45 forces the lever arm 161^a up into engagement with the surface 130^b of the cam. Such operation rocks the lever 163 on its fulcrum 162, and as the drop from the portion 130^a to the portion 130^b is abrupt, the correspondingly abrupt movement 50 of the lever 163^b causes a quick downward movement of the shaft 156.

55 The link work described above will be thereby actuated to swing the bar 150 outwardly and the bar 151 downwardly to carry the siphon tip 97 against the side wall and into the lowest point in a container in a canted position in the receiver 32.

With the continued rotation of the cam 130 the portion 130^a again actuates the lever 161 60 against the spring 159 and the lever 161 carries the rod 156 upwardly returning the link work to its full line position of Fig. 1 in which the siphon tip 97 is returned to inoperative position. The spring 163 cushions the return action and tends 65 to hold the parts in their full line inoperative position of Fig. 1.

It should also be noted that if the link work is strained while the cam 130 limits movement of the lever 161, the spring 163 serves to protect 70 the link work by permitting only limited movement.

In Fig. 2, the cam 148 has the same function as the cam 130 in the type of apparatus just described.

75 The rod 156^a is provided with a collar 165 between which and the housing 155 is the operating spring 166. I mount in the bottom 131^a of the support 131, a slideable hollow member 167 having a roll 168 adapted to travel over the cam 148. The member 167 receives the lower end

of the rod 156^a and is slotted as at 167' to receive the stud 169 on the rod 156^a. The rod 156^a is provided with a collar 170 between which and the member 167 is a spring 171.

As the support 131 rotates, the roll 168 will be 5 carried off the cam 148 permitting the spring 166 to actuate the rod 156^a to lower the siphon tip 97 as has been described. The spring 166 has therefore a function similar to the spring 158.

When the complete rotation of the support 10 131 carries the roll 168 onto the cam 148 again, the spring 171 actuates the rod 156^a similarly to the spring 163.

When the roll 168 is on the cam 148, limited movement of the tip 97 or the linkwork is permitted by the spring 171 and the length of the slot 168.

When this mechanism, the siphon tip 97 may be positioned in desired fluid exhausting position regardless of the variation in the distance 20 from the bung hole to the wall. This mechanism is adequately protected so that it will not be unduly strained when the tip 97 has reached the lowest point possible whether in a container having a bung hole on its side or in the end. It 25 is to be noted, that different containers may be supported in slightly different positions due to the supports 38 and 38^a and 38^b.

In each of the types of apparatus, the cams 130 (Fig. 1) and 148 (Fig. 2) restore the siphon 30 to the positions shown in Figs. 1 and 2 to permit the removal of reconditioned containers at which time all delivery conduits to the receivers are closed. In Fig. 1, I have shown the valve as 35 delivering rinsing fluid into a container. As this was done for the purpose of illustrating the fluid circulating system I have shown the consistent position of the siphon in dotted lines.

In the type illustrated in Figs. 3 and 4 I have 40 indicated apparatus in which containers are manually progressed from station to station in each of which specific operations are performed. In such apparatus, drying alone presents a serious problem and I have shown only so much of the apparatus as relates to that operation.

The container receiver 32^a is secured to the rear wall 180 as at 181 and to the front wall 182 as at 183.

The container receiver 32^a consists of a pair of side members 184 and cross members 185, 186 and 50 187. The members 184 are spaced apart to permit a container C to be positioned on its side in a zone limited by the cross members 186 and 187. The members 184 are formed with recesses 188 which define a zone to receive the edges of a container C¹.

Both of the containers C and C¹ are therefore held in a canted position. On the ends of each of the side members 184 a pair of supports 189 and 190 are secured. These supports are bent inwardly to hold a pair of members indicated as at 191 which are closed at each end as at 192 to define a slot.

An air conduit 193 enters through the rear wall 180 and includes a portion 194 supported on a shelf 195 braced as at 196. From a suction pump indicated as at 197, a suction pipe 198 extends through the rear wall 180 and is supported on the shelf 195. On the shelf 195, the air conduit 193 and the suction pipe 198 are provided with 65 swivel joints 199 beyond which they extend through the rear wall 180 as through the aperture 200. The conduit 193 and the suction pipe 198 include a swivel joint 201 beyond which there 70 are elbow joints 202. From the joints 202, the 75

conduits 193 and 198 extend upwardly through the slot between the members 191.

The air conduit 193 is provided with an elbow 203 into which is threaded the curved member 204 to enter the bung hole of containers supported in the receivers 32a. The member 204 is provided with a plurality of jets indicated as at 205.

The suction pipe 198 is shaped to enter the elbow 203 and pass through the member 204 to provide a tip 206 curved similarly to the member 204. The end of the member 204 is suitably sealed to the tip 206.

In apparatus of this type, containers are placed in the receivers 32a and it will be noted that they may be positioned so that their bung holes, whether on the end or on the side, may be entered by the member 204 and the tip 206. When the containers are so positioned, the fluid exhausting means just described may be pivoted to enter the bung hole and reach the lowest point therein.

The joints 199 permit the pivot point of the fluid exhausting member, the joints 201, to be varied so that the fluid exhausting member may be positioned to enter any bung hole when its container has been properly positioned in the receiver 32a. The tip 206 is resilient, permitting the thorough reconditioning of all containers.

The air line 193 may be controlled by the valve 207 or the valve 208 and suitable switches may be positioned near either of said valves to control the suction pump 187.

While this apparatus is extremely simple, it is effective for use where the number of containers to be reconditioned is not large.

Conclusion

My invention, as illustrated in the typical embodiments, permits the thorough drying of containers having bung holes. As this may be done with certainty, it is possible to determine from the desired capacity what automatic and semi-automatic controls are necessary to give the greatest economy and efficiency.

What I therefore claim and desire to secure by Letters Patent is:—

1. In apparatus for reconditioning the interiors of containers comprising a container receiver, and a suction tube operatively mounted within said receiver, said tube including an adjustable extensible and pivotable tip, means for moving said tip to fluid exhausting position, said means comprising a plurality of links pivotally connected to each other, one of said links being operatively connected to said tip, a rod operatively connected to another link, a lever operatively engaging said rod, and means for rocking said lever whereby said rod actuates said links to swing said tip downwardly to fluid exhausting position.

2. In apparatus for reconditioning the interiors of containers comprising a container receiver, and a suction tube operatively mounted within said receiver, said tube including an adjustable extensible and pivotable tip, means for moving said tip to fluid exhausting position, said means comprising a plurality of links pivotally connected to each other, one of said links being operatively connected to said tip, a rod operatively connected to another link, a lever operatively engaging said rod, and means for rocking said lever whereby said rod actuates said links to swing said tip downwardly to fluid exhausting position, and means

for oppositely rocking said lever to return said tip to inoperative position.

3. In apparatus for reconditioning the interiors of containers comprising a container receiver, and a suction tube operatively mounted within said receiver said tube including an adjustable extensible and pivotable tip, means for moving said tip to fluid exhausting position, said means comprising a plurality of links pivotally connected to each other, one of said links being operatively connected to said tip, a rod operatively connected to another link, a lever operatively engaging said rod, and means for rocking said lever whereby said rod actuates said links to swing said tip downwardly to fluid exhausting position, means for normally holding said lever in position to maintain said tip in operating position and means for oppositely rocking said lever to return said tip to inoperative position.

4. In apparatus for reconditioning the interiors of containers comprising a container receiver, and a suction tube operatively mounted within said receiver, said tube including an adjustable extensible and pivotable tip, means for moving said tip to fluid exhausting position, said means comprising a plurality of links pivotally connected to each other, one of said links being operatively connected to said tip, a rod operatively connected to another link, a lever operatively engaging said rod, and means for rocking said lever whereby said rod actuates said links to swing said tip downwardly to fluid exhausting position, means for normally holding said lever in position to maintain said tip in operating position and means for oppositely rocking said lever to return said tip to inoperative position.

5. In apparatus for reconditioning the interiors of containers comprising a container receiver, a suction tube mounted in said receiver and including a pivotable and extensible tip, means adapted to pivot and extend said tip into the lowest point in said container and to return it to position to permit the container to be removed from said receiver, and means pivotally connected to said tip extending means including a spring normally holding said positioning means in fluid exhausting position, means adapted to compress said spring to move said positioning means to carry said tip to an inoperative position, means actuating said compressing means, and means cushioning movement of said positioning means when said spring is dominated by said compressing means.

6. In apparatus for reconditioning the interiors of containers having bungholes comprising a base, a container receiver rotatably mounted on said base, and a suction tube mounted in said receiver and including an extensible tip, means to extend said tip into the lowest point in a container when positioned in said receiver, and to return it to a position to permit the container to be removed from said receiver, said means comprising a rod pivotally connected to said tip, a spring urging said rod downwardly to maintain said tip in fluid exhausting position, a sleeve on said rod and having a limited zone of longitudinal movement relative thereto, a cam on said base adapted to be contacted by said sleeve, as said receiver rotates over said base to move said rod to carry said tip to an inoperative position.

7. In apparatus for reconditioning the interiors of containers having bungholes comprising a container receiver, a suction tube mounted in

5 said receiver, said tube including a pivotable and extensible tip, means adapted to pivot and extend said tip into the lowest point in said container and to return it to position to permit the container to be removed from said receiver, said means comprising a rod, operative connections between said rod and tip, a lever operatively connected to said rod, a spring urging said lever in one direction, means adapted to compress said 10 spring and to rock said lever in the opposite direction, a positive connection between said lever and rod when said spring is actuating said lever, and a resilient connection between said lever and rod, when said compressing means is in control 15 of said lever.

8. In apparatus for reconditioning the interiors of bung holed containers, a container receiver, a suction tube mounted in said receiver to enter bungholes, said tube including in its bung 20 hole entering portion, a pivotable portion and a tip slidably mounted thereon, an arm pivotally connected to said tip, a second arm pivotally connected to said first arm and to said receiver and means adapted to pivot one or both of said 25 arms to adjust the position of said tube to exhaust fluid from the lowest part of a container or to permit said container to be removed, said means comprising a lever pivotally connected to said receiver and a link pivotally connected to 30 said lever and said first arm, a rod, a link pivotally connecting said lever and said rod, and means to raise and lower said rod.

9. In apparatus for reconditioning the interiors of bung holed containers, a container receiver, a suction tube mounted in said receiver to enter bungholes, said tube including in its bung hole entering portion, a pivotable portion and a tip slidably mounted thereon, an arm pivotally connected to said tip, a second arm pivotally connected to said first arm and to said receiver and means adapted to pivot one or both of said arms to adjust the position of said pivotable portion and said tip to exhaust fluid from the lowest part of a container or to permit said container to be 45 removed, said means comprising a lever pivotally connected to said receiver and a link pivotally connected to said lever and said first arm, a rod, a link pivotally connecting said lever and said rod, and means to raise and lower said rod, said last named means including a spring to 50 actuate said rod to effect an operative position of said pivotable portion and said tip and a cam to actuate said rod to position said pivotable portion and said tip inoperatively.

55 10. In apparatus for reconditioning the interiors of bungholed containers, a container receiver, a suction tube mounted in said receiver to enter bungholes, said tube including in its bung hole entering portion, a pivotable portion and a tip slidably mounted thereon, an arm pivotally connected to said tip, a second arm pivotally connected to said first arm and to said receiver and means adapted to pivot one or both of said arms to adjust the position of said pivotable portion and said tip to exhaust fluid from the lowest part of a container or to permit said container to be removed, said means comprising a lever pivotally connected to said receiver and a link pivotally connected to said lever and said first arm, a rod, a link pivotally connecting said lever and said rod, and means to raise and lower said rod, said last named means including a spring to actuate 65 said rod to effect an operative position of said pivotable portion and said tip and a cam to actuate said rod to position said pivotable portion

and said tip inoperatively, and resilient means to permit said rod to move when said cam resists the action of said spring.

11. In apparatus for reconditioning the interiors of bung holed containers, a container receiver, a suction tube mounted in said receiver to enter bungholes, said tube including in its bung hole entering portion a pivotable portion and a tip slidably mounted thereon, an arm pivotally connected to said tip, a second arm 10 pivotally connected to said first arm and said receiver and means adapted to pivot one or both of said arms to carry said pivotable portion and said tip into position to exhaust fluid or into inoperative position, said means comprising a lever pivoted to said receiver, a link pivotally connected to said lever and said first arm, a rod, and a link connecting said lever and said rod and means to actuate said rod, said actuating means comprising a second lever, a catch on said 20 rod to be engaged by movement of said second lever in one direction, a spring carried by said rod in contact with said second lever, a second spring adapted to actuate said second lever to cause an engagement with said catch, and a 25 rotatable cam adapted to resist the action of said second spring and to move said second lever against said first named spring.

12. In apparatus for reconditioning the interiors of bung holed containers, a base, a support rotatably mounted on said base, a container receiver in said support, a suction tube mounted in said receiver to enter bungholes, said tube including in its bung hole entering portion a pivotable portion and a tip slidably mounted thereon, an arm pivotally connected to said tip, a second arm pivotally connected to said first arm and said receiver and means adapted to pivot one or both of said arms to carry said tip into position to exhaust fluid or into inoperative position, 30 said means comprising a lever pivoted to said receiver, a link pivotally connected to said lever and said first arm, a rod and a link connecting said lever and said rod, a spring to actuate said rod, and a cam on said base adapted to actuate 35 said rod against said spring.

13. In apparatus for reconditioning the interiors of bung holed containers, a base, a support rotatably mounted on said base, a container receiver in said support, a suction tube including 40 in its bung hole entering portion a pivotable portion and a tip slidably mounted thereon, an arm pivotally connected to said tip, a second arm pivotally connected to said first arm and said receiver and means adapted to pivot one or both of said arms to carry said tip into position to exhaust fluid or into inoperative position, said means comprising a lever pivoted to said receiver, a link pivotally connected to said lever and said first arm, a rod and a link connecting said lever and said rod, a spring to actuate said rod, a sleeve on said rod, said sleeve and said rod having a zone of relative sliding movement and a resilient member connecting said sleeve and said rod, and a cam on said base adapted to actuate 55 said sleeve against said spring.

14. In apparatus for reconditioning the interiors of containers comprising a container receiver and a suction tube operatively mounted within said receiver, said tube including a pivotable portion and a tip slidably mounted thereon, means for moving said tip to fluid exhausting position within a container, said means comprising a plurality of links pivotally connected to each other, one of said links being operatively 60

75

- connected to said tip, and actuating means for said tip moving means.
15. In apparatus for reconditioning the interiors of bung holed containers, a container receiver, a suction tube mounted in said receiver, said tube including a bung hole entering portion including a pivotable portion and a tip adjustably mounted thereon, an arm pivotally connected to said tip, a second arm pivotally connected to said first arm and to said receiver, and means adapted to pivot one or both of said arms to adjust the position of said pivotable portion and said tip to exhaust fluid from the lowest part of a container or to permit said container to be removed.
16. In apparatus for reconditioning the interiors of bung holed containers, a container receiver to support containers, a suction tube mounted in said receiver including a bung hole entering portion including a pivotable member and a tip adjustably mounted therein, common means connected to said tip to pivot said member and to position said tip into operative and inoperative position after a container has been positioned in said receiver.
17. In apparatus for reconditioning the interiors of bungholed containers, a container receiver to support containers, a suction tube mounted in said receiver including a bunghole, 10 entering portion including a pivotable member and a tip slidably mounted therein, means connected to said tip to pivot said member into operative or inoperative position after a container has been positioned in said receiver, said means being adapted to cause a sliding of said tip on said member to ensure the extension of said tip into the lowest point in a container.

SAMUEL F. KIMBALL.
